[57] CLAIM

The ornamental design for a furniture hinge arm, substantially as shown and described.

DESCRIPTION

FIG. 1 is a top plan view of the furniture hinge arm of our new design;

FIG. 2 is a bottom plan view thereof;

FIG. 3 is an end view thereof, as viewed from the right of FIG. 1;

FIG. 4 is an end view thereof, as viewed from the left for FIG. 1; and

FIG. 5 is a side elevation view thereof, the opposite side being a mirror image.

FIG. 1

FIG. 2

FIG. 3

FIG. 4

FIG. 5
